UNITED STATES PATENT OFFICE.

JAMES McCARTHY, OF LONG ISLAND CITY, NEW YORK, ASSIGNOR TO HALL BORCHERT DRESS FORM COMPANY, OF NEW YORK, N. Y., A CORPORATION OF NEW JERSEY.

DRESS FORM.

1,425,877.

Specification of Letters Patent. Patented Aug. 15, 1922.

Application filed October 22, 1919. Serial No. 332,513.

To all whom it may concern:

Be it known that I, JAMES McCARTHY, a citizen of the United States, and resident of Long Island City, in the county of Queens 5 and State of New York, have invented certain new and useful Improvements in Dress Forms, of which the following is a specification.

This invention involves certain improvements in dress forms and more particularly that type of dress form in which there is a body or manikin of the desired size and shape and formed of comparatively stiff papier mâché or other similar material where- 15 by a light and rigid body is formed upon which the dress or other clothing may be fitted. One of the main objects of my invention is to provide a simple and inexpensive support by means of which the body 20 may be held at the desired elevation or may be compactly telescoped with the support for shipment or storage.

A further object of my invention is to so construct and design the support that the 25 form may be easily and quickly removed therefrom and placed on a table or other flat supporting surface and used in that position.

A further object of my invention is to facilitate a proper and symmetrical fitting 30 of the garment to the form and the exact center line up and down the front and back, accurately determined even when the form is entirely or substantially concealed within the garment.

35 In the accompanying drawings to which reference is to be had, I have illustrated certain embodiments of my invention but it will, of course, be evident that I do not desire to be strictly limited to the details 40 illustrated as various changes may be made within the spirit of my invention without departing from the scope thereof as defined in the appended claims. In these drawings:

Figure 1 is a side elevation, portions of 45 the form and support being shown in section and the form being in raised position;

Figure 2 is a section similar to Figure 1, but showing the parts in position for shipment or storage;

50 Figure 3 is a similar view of the dress form with the parts in the position they occupy when the form is supported upon a table or other similar surface;

Figure 4 is a bottom view of the form 55 shown in Figures 1, 2 and 3;

Figure 5 is a bottom view of a slightly modified construction;

Figure 6 is a vertical section of the lower portion of the form shown in Figure 5; and

Figure 7 is a sectional detail.

The form is illustrated as including a hollow shell or body 10 preferably formed of papier mâché or other similar comparatively light rigid material. This body is non-adjustable, that is, it is made of the desired shape and size for the particular user. In practice these bodies are made up in a large number of different sizes and shapes and the purchaser selects one best suited to her needs. As an important feature of my 65 invention I provide the body with two comparatively low narrow ridges 11 extending vertically along the front and rear surfaces from the lower edge to the neck and in the medial plane. These are molded in the 70 papier mâché at the time the body is made. The mold in which the body is formed is preferably provided with a corresponding groove into which the papier mâché may enter at the time it is being molded. These 75 ridges on the body do not project out sufficiently far to be noticeable and do not interfere with the proper fitting of a garment to the form, but they are of sufficient height and narrowness to enable the dressmaker or 80 other user to feel them when passing the hand across the form. They may be readily felt even when the garment is fitted to the form so that the user may readily determine the exact center line of the front and back 85 90 and, therefore, more easily make the garment symmetrical. In practice the papier mâché body is preferably covered with a thin semi-elastic fabric, such as jersey, which gives the form an attractive appearance but 95 which does not prevent the ridges 11 from being easily felt.

As a further important feature of my invention the body of the form is provided with a bottom wall 12 preferably of wood 100 and spaced a slight distance above the lower projecting edge 13 of the body wall. No part which is permanently secured to this wood bottom extends below said edge so that when the form is removed from its supporting stand it may be placed directly upon a table, as shown in Figure 3, and will rest on the edge 13.

The supporting stand includes a base 14 having a tube 15 rigidly secured thereto. 110

Mounted for telescoping movement within this tube is a rod 16, the tube being held in any desired relative axial adjustment by a set screw 17, preferably having a butter-fly head whereby it may be readily operated by hand. The bottom 12 has a collar 18 projecting upwardly through an aperture therein and held in place by a flange 19 secured to the underside of the bottom 12 by nails, 10 screws or other suitable attaching means. The passage through the collar 18 is such as to receive the rod 16 and the thickness of the flange 19 is such that it does not project below the edge 13 of the body wall. The rod 15 16 is so connected to the base 12 that it may be moved lengthwise in respect thereto or may be held against such lengthwise movement. As shown, the rod has a pair of spaced apertures therethrough adjacent to its 20 upper end and at a distance apart substantially equal to the length of collar 18 and through these are extended cotter pins 20 and 21. These hold the rod substantially rigid in respect to the body and permit the 25 rod to be pulled up or lowered in respect to the base 14 and tube 15, when the said screw 17 is loosened. Thus the form may be supported from the base at any desired elevation by loosening and tightening the set screw 17. 30 The rod 16 is of such length that it projects into the tube 15 for some little distance even when the form is supported at what would ordinarily be the maximum elevation for use. The collar 17 is of such length that 35 it forms an adequate guide and firmly supports the form in an upright position.

The base 12 is provided with a second aperture 22 of such size as to receive the tube 15. The collar is preferably placed 40 nearer to the front than to the back of the base and the aperture 12 is usually near the center of the base although these positions will vary with different shaped forms. When it is desired to store or ship the form the cotter 45 pin 21 may be removed so as to permit the rod 16 to be moved up into the body as shown in Figures 2 and 3 and the set screw 17 is removed so that the body may be lowered to the base with the tube 15 projecting up 50 through the aperture 22, as shown in Figure 2.

This brings the bottom wall 12 of the form down directly to the base 14 and thus the form when in this position occupies the 55 minimum space and may be shipped in a box of the minimum size.

By means of my invention I provide a very inexpensive but serviceable form which may be sold at a low price due to the 60 proved novel and simplified construction. It will be apparent that somewhat similar results might be secured by very much more expensive and elaborate construction, but one of the objects of my invention is to get all of

the necessary and desired functions at as 65 low a cost as possible.

Various changes may be made in the details of construction. For instance, it is not necessary that the bottom wall 12 of the form be a complete wall as shown in Figure 70 4. Such a complete bottom wall 12 may be held in place by nails or other suitable screwing means as shown in Figures 1, 2 and 3. The bottom may be additionally held in place and less material used in making the 75 bottom as shown in Figures 5 and 6. Here the bottom wall 12^a is merely in the form of a board extending from the front to the rear and the wall of the body has its edge 13^a folded over against the under side of the 80 board. This provides additional means for better holding the bottom in place and also provides a wider and more serviceable supporting edge for the body, in case the latter is to be used on a table, as shown in Figure 85 3. It will be noted from Figure 6 that the thickness of the edge 13^a of the body wall is greater than the thickness of the flange 19. With the partial bottom, as shown in Figure 90 5 the user may insert the hand into the lower end of the body and remove the cotter-pin 20 so that the rod may be stored in the tube 15 instead of in the body as shown in Figures 95 2 and 3. When stored in the bottom, the lower end of the rod is preferably slightly deformed, flattened or riveted over so that it cannot pass through the collar 18. Instead of an upper cotter pin 20 the upper end may be riveted over or deformed to prevent withdrawal.

Having thus described my invention what I claim as new and desire to secure by Letters Patent is:

1. A dress form having a hollow rigid, non-adjustable, one-piece body formed of papier 105 maché and provided with a low ridge, integral with the wall and extending vertically along the medial line.

2. A dress form having a hollow rigid, non-adjustable, one-piece body formed of 110 papier maché, the front and back walls thereof being each provided with a ridge extending vertically along the medial line.

3. A dress form including a form body having a bottom provided with a pair of 115 apertures, a base, a standard including a pair of separable telescoping members each shorter than said body, one rigid with said base and the other projecting through one of said apertures, means at the upper end of 120 said last mentioned member for preventing the removal of said member from said aperture, means for permitting or preventing the sliding movement in said aperture, means for preventing or permitting telescoping of said standard members, said 125 standard members being separable whereby one member may be moved upwardly to sub-

stantially its entire length in its aperture of said bottom member and the standard member rigid with said base may be inserted to substantially its full length in the other 5 aperture of said bottom, and said bottom and form body supported on said base.

4. A dress form including a form body having a bottom provided with a pair of apertures, a base, a standard including a 10 pair of separable telescoping members each shorter than said body, one rigid with said base and the other projecting through one of said apertures, means for normally locking the upper end of said second mentioned 15 member against endwise movement through said aperture with the member and the

frame body in predetermined relative positions, means for preventing or permitting telescoping of said standard members, said standard members being separable whereby 20 one member may be moved upwardly to substantially its entire length in its aperture of said bottom member and the standard member rigid with said base may be inserted to substantially its full length in the other 25 aperture of said bottom, and said bottom and form body supported on said base.

Signed at New York in the county of New York and State of New York this 16th day of October A. D. 1919.

JAMES McCARTHY.
